UNITED STATES PATENT OFFICE

2,412,941

METHOD OF APPLYING FITTINGS TO ROPES

Gordon H. Bannerman, Worcester, Mass., and James M. Curran and Glen H. Trout, Omaha, Nebr., assignors to The American Steel and Wire Company of New Jersey, a corporation of New Jersey

Continuation of application Serial No. 175,165, November 17, 1937. This application June 5, 1940, Serial No. 339,026

1 Claim. (Cl. 29—148)

1

This invention relates to a method of applying rope fittings and is particularly concerned with the application of a fitting to a wire rope in such a manner that the fitting is positively fixed against movement longitudinally of the rope when the latter is subjected to its normal operating tension.

By way of a specific example, the accompanying drawings illustrate the application of a fitting in such a manner as to anchor the swinging carrier arm of a wire rope tramway or conveyer against movement longitudinally of the conveyer rope, the various figures being as follows:

Figure 1 is a transverse view of the conveyer rope and one of the arms;

Figure 2 is a side view of Figure 1;

Figure 3 is a transverse section of the fitting;

Figure 4 is a longitudinal section of the same; and

Figures 5 and 6 are elevations taken in different directions of part of the equipment used in the application of the fitting.

In these drawings, the tramway or conveyer rope 1 is made of wire, and supports a series of depending arms of which only one, numbered 2, is illustrated. This arm connects with the rope by way of spaced heads 3 through offsets 4, each head consisting of two semi-cylindrical halves interfastened by rivets 5 so as to relatively loosely embrace the rope 1, whereby the hanger arm 2 may swing relative the latter.

The present invention is exemplified by a lug 6 which is fixed to the rope 1 between the heads 3 so as to anchor the latter against movement longitudinally of this rope. This lug is in the form of interfitting semi-cylindrical parts having cooperative piano hinge elements 7 on their respective abutting edges through which pins 8 may be driven to effect interfastening. The two semi-cylindrical parts of the lug do not directly engage the rope 1 but are internally recessed, as at 9, so as to retain liners 10 in such a fashion that the latter are interposed between the parts and the rope 1. These liners 10 have their inside surfaces helically grooved, as at 11, in such a fashion that these grooves fit the individual strands of the wire rope.

A particularly characterizing feature of the above fitting or lug 6 is that it constricts the rope to a diameter substantially less than that diameter to which the rope is reduced by the operating tension which it is designed to normally accommodate. It has been found that by so applying the fitting it remains absolutely fixed relative the rope because it exerts its constricting

2

tendency respecting the latter even when the rope's diameter is reduced by its operating tension.

The rope 1 is placed under tension at least equaling and preferably exceeding 30% of its ultimate strength, the normal operating tension for which it is designed. The liners 10 are, of course, positioned within the lug and should be made from a material that is slightly plastic under pressure yet which has the ability to withstand repeated impact stresses resulting when the lugs pass over the rollers of the tramway system of which the rope is a part. Assuming the lug to be made of steel, copper is a good example of a desirable liner material. Piano hinge elements 7 of the two parts of the lug 6 are so constructed that the holes in the respective elements are slightly out of registration at this time, registration being effected by placing the lugs between the jaws 12 of a suitable hydraulic jack 13, these jaws embracing the parts of the lug 6 to bring the holes of its piano hinge elements to registration, this constricting the rope 1 to a diameter less than that to which it is reduced by the applied tension and permitting insertion of the pins 8, the ends of which are then upset, to retain them in position. Pressure exerted by the jaws 12 is sufficient to cause the copper liners to flow slightly and creep between the individual wires of the strands of the rope 1.

The advantage of the resulting installation respecting the ability of the lug 6 to remain fixed in position even when the rope 1 is tensioned so that its diameter slightly reduces has already been mentioned. A further advantage is that a wire rope even when it has a wire center or core is subject to some internal wear whereby its diameter is continuously reduced during service.

Due to the fact that the lug 6 is constricting the rope to a diameter considerably smaller than its normal diameter, the lug does not loosen even when such internal wear reduces the rope's diameter. Due to the fact that external wear is occurring on the portions of the rope not protected by the lug 6, the service life of the rope reaches its end prior to the time the internal wear of the rope within the lug 6 causes loosening of the latter.

It is to be understood that the external wear mentioned is caused by the rope frictionally working against various surfaces, such as that of the sheave 14 illustrated in the drawings.

This application is a continuation of our co-pending application of the same title, bearing Serial No. 175,165 and filed November 17, 1937.

We claim:

A method of applying a fitting to a rope, said fitting being adapted to encircle and constrict said rope so as to be positioned against movement longitudinally of the same, said method being characterized in that said rope is tensioned sufficiently to reduce its normal diameter during the application of said fitting, the force used to

5

so tension said rope exceeding the normal working tension for which the same is designed, and said method being further characterized in that the latter is applied to said rope while the same is so tensioned so as to constrict said rope with a force sufficient to still further reduce its normal diameter.
